(57) **CLAIM**

The ornamental design for a front support bracket for vehicle shifter as shown and described.

DESCRIPTION

FIG. 1 is a top, right-side, front perspective view showing my new design;

FIG. 2 is a top, right-side, rear perspective view thereof;

FIG. 3 is a top, rear, left-side perspective view thereof;

FIG. 4 is a top, left-side, front perspective view thereof;

FIG. 5 is a bottom, left-side, rear perspective view thereof;

FIG. 6 is a bottom, left-side, front perspective view

FIG. 7 is a bottom, right-side, rear perspective view thereof;

FIG. 8 is a bottom, front, right-side perspective view thereof;

FIG. 9 is a front, left-side perspective view thereof;

FIG. 10 is a front, right-side perspective view thereof;

FIG. 11 is a rear, right-side perspective view thereof;

FIG. 12 is a rear, left-side perspective view thereof;

FIG. 13 is a front view thereof;

FIG. 14 is a rear view thereof;

FIG. 15 is a left-side view thereof;

FIG. 16 is a right-side view thereof;

FIG. 17 is a top plan view thereof; and,

FIG. 18 is a bottom plan view thereof.

The dash-dash broken lines in the drawings depict portions of the front support bracket for vehicle shifter that form no part of the claimed design.
